UNITED STATES PATENT OFFICE.

ZACHARIAH L. TRAINHAM AND HARRY E. EASTMAN, OF RICHMOND,
VIRGINIA.

SWITCH-OPERATING MECHANISM.

SPECIFICATION forming part of Letters Patent No. 739,749, dated September 22, 1903.

Application filed April 16, 1903. Serial No. 152,975. (No model.)

To all whom it may concern:

Be it known that we, ZACHARIAH L. TRAINHAM and HARRY E. EASTMAN, citizens of the United States, residing at Richmond, in the county of Henrico and State of Virginia, have invented new and useful Improvements in Switch-Operating Mechanism, of which the following is a specification.

Our invention relates to new and useful improvements in switch-operating mechanism especially adapted for use upon street-railways; and its object is to provide mechanism of simple construction which can be readily operated by the motorman or any other person upon the car without lessening the speed of the car.

With the above and other objects in view the invention consists in providing a pivoted disk having a curved slot therein, within which is mounted the end of a link connected to a bell-crank lever, one arm of which projects above the road-bed and is adapted to be contacted and depressed by suitable mechanism arranged upon a car. The tongue of the switch has a laterally-extending arm projecting from its pivot, and rods connect this arm with the disk, so that when the disk is moved in either direction the arm will be moved therewith, thereby shifting the tongue.

The invention also consists in the further novel construction and combination of parts hereinafter more fully described and claimed, and illustrated in the accompanying drawings, showing the preferred form of our invention, and in which—

Figure 1 is a longitudinal section through our improved switch-operating mechanism; and Fig. 2 is a plan view thereof, the casing being shown in section.

Referring to the figures by numerals of reference, 1 is a casing of suitable construction, within the top 2 of which is fulcrumed a bell-crank lever 3. The upper arm 4 of this lever forms a blade, which extends upward through a slot 5 in the top 2. The remaining arm of the lever is loosely connected to a link having a forked end 7, within which is journaled a roller 8. This roller is adapted to travel within the curved slot 9, formed within a disk 10, which is fulcrumed upon a pin 11, arranged within the casing. A spring 12

is connected at opposite ends to the lower arm of the bell-crank lever and to the bottom of casing 1 at a point adjacent to pin 11. The switch-tongue 13 has an arm 14, which extends laterally from its fulcrum 15, and this arm projects through a slot 16 in the side of casing 1, and its inner end is connected, by means of a rod 17, with the disk 10 at one side of the fulcrum thereof. A lever 18 is fulcrumed within casing 1 at a point adjacent to the arm 14, and one end of this lever is connected to arm 14 at a point adjacent to rod 17 by a rod 19, and another rod 20 connects the other end of lever 18 with the disk 10 at the side of its fulcrum opposite to that to which the rod 17 is secured.

In order to operate this mechanism, the car approaching the switch is preferably provided with a lever 21, having an arm 22 extending upward therefrom through the platform and provided with a flat plate 23. A spring 24 holds the lever normally raised, and a roller 25 is journaled in the lower end of the lever. When the car approaches the switch, the lever 21 is depressed, as shown in Fig. 1, and brought into contact with the blade 4 of the bell-crank lever and causes said blade to move downward into the slot 5. This movement of the blade will swing the other arm 14 of the bell-crank lever so as to draw the link 6 in a direction away from disk 10, and this disk will be partly rotated thereby and spring 12 extended. The rods 17 and 20 will be moved in opposite directions, and arm 14 will be so moved as to swing the tongue 13 in the desired direction. As soon as the roller 25 leaves the blade 4 the spring 12 will complete the movement of the roller 8 within the slot and will hold the disk 10 in the position illustrated in dotted lines, Fig. 2. When it is desired to move the switch-tongue in the other direction, the operation above described is repeated. By providing the second lever 18 within casing 1 a pull is always exerted upon the arm 14 during the shifting thereof. It will be seen that the device is extremely simple in construction, and a switch-tongue can be quickly and accurately shifted without stopping the car approaching the same.

In the foregoing description we have shown the preferred form of our invention; but we

do not limit ourselves thereto, as we are aware that modifications may be made therein without departing from the spirit or sacrificing any of the advantages thereof, and we therefore reserve the right to make such changes as fairly fall within the scope of our invention.

Having thus described the invention, what is claimed as new is—

- 10 1. In switch-operating mechanism of the character described, the combination with a pivoted disk having a slot therein; of a bell-crank lever, one arm of which is adapted to be depressed by suitable mechanism upon a car, a crank connected to the other arm of the lever, a forked end thereto, a roller journaled within said end and adapted to travel within the slot, a spring connected to the bell-crank lever, a pivoted tongue, an arm 15 extending laterally from the fulcrum thereof, a lever, rods connecting the disk and lever with the arm, and a rod connecting the lever with the disk.
- 20 2. In switch-operating mechanism of the character described, the combination with a casing; of a disk pivoted therein and having a slot, a bell-crank lever fulcrumed within

and extending above the casing, a link connected to the lever and having a forked end, a roller journaled within said end and adapted to travel within the slot, a spring connecting the lever with the casing, a pivoted switch-tongue, an arm extending laterally from the fulcrum thereof, a lever centrally fulcrumed within the casing, rods connecting the disk 35 and lever with the arm, and a rod connecting the disk and lever.

3. In switch-operating mechanism of the character described, the combination with a casing having a pivoted disk therein, and 40 means for partly rotating said disk in either direction; of a pivoted switch-tongue, an arm extending from the fulcrum thereof, a lever fulcrumed in the casing, rods connecting the disk and lever with the arm, and a rod connecting said lever and the disk.

In testimony whereof we affix our signatures in presence of two witnesses.

ZACHARIAH L. TRAINHAM.
HARRY E. EASTMAN.
